Specification for Design.

Patented Jan. 8, 1918.

Application filed October 15, 1917. Serial No. 196,766. Term of patent 7 years.

To all whom it may concern:

Be it known that I, JOHN DITTRICK, a subject of the King of Great Britain, residing in the township of Elmsley, in the county of Lanark, Province of Ontario, Dominion of Canada, have invented a new, original, and ornamental Design for a Toy Cannon, of which the following is a speci-

fication, reference being had to the accompanying drawings, forming part thereof.

The figure is a perspective view of the toy cannon, showing my new design.

I claim:

The ornamental design for a toy cannon, as shown.

JOHN DITTRICK.
